AUXILIARY SHUTTLE BOX FOR SHUTTLE CHANGING LOOMS

Filed Aug. 14, 1930

UNITED STATES PATENT OFFICE

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

AUXILIARY SHUTTLE BOX FOR SHUTTLE CHANGING LOOMS

Application filed August 14, 1930. Serial No. 475,247.

This invention relates to a shuttle changing loom of the type in which the auxiliary shuttle is received in an auxiliary shuttle box upon the occasion of weft replenishment. 5 The exhausted shuttle is picked into this auxiliary shuttle box in the usual way, but the shuttle is immediately discharged from the auxiliary box and from the loom, and no shuttle is ever picked out of the auxiliary shuttle 10 box. Consequently the exhausted shuttle is never acted upon by the regular loom picker after it enters the auxiliary box and it need have no operative relation thereto.

It is the object of my invention to provide 15 means for bringing an exhausted shuttle to rest in the auxiliary shuttle box independently of any action of the loom picker and for holding the exhausted shuttle in such position until discharged therefrom.

20 A further object of my invention is to provide means by which an exhausted shuttle will be stopped in a definite and predetermined longitudinal position in the auxiliary shuttle box, the position being such that the 25 shuttle may be ejected from the box without interfering with the loom picker.

My invention further relates to arrangements and combinations of parts which will be hereinafter described and more particularly pointed out in the appended claims.

30 A preferred form of the invention is shown in the drawings, in which

Fig. 1 is a front elevation of parts of a shuttle-changing loom embodying my improvements;

Fig. 2 is a similar view, showing an exhausted shuttle received in the auxiliary box;

Fig. 3 is an enlarged side elevation of my improved shuttle stopping device;

40 Fig. 4 is a transverse sectional view, taken along the line 4-4 in Fig. 3, and

Fig. 5 is a detail bottom view, looking in the direction of the arrow 5 in Fig. 3.

Referring to the drawings, I have indicated 45 portions of a shuttle changing magazine M, a lay 10, an upper or regular shuttle box 11 and a lower or auxiliary shuttle box 12. The boxes 11 and 12 are mounted on a lifter rod 13 and are shifted vertically in the lay 50 10 by the usual box lifting mechanism, not

shown. The usual picker 15 is mounted on a picker stick 16 and is engaged by the shuttle S as it enters the upper or regular box 11, this position of the parts being shown in Fig. 1.

The parts thus far described are in general of the usual construction and in themselves form no part of my present invention, which relates particularly to certain changes embodied in the lower or auxiliary shuttle box 12.

The rear wall of the lower auxiliary shuttle box 12 is provided with serrated blocks 22 and 24 projecting forward therefrom and positioned respectively in the upper and lower rear corners of the shuttle box. Stop members 30 and 31 are provided with serrated rear surfaces to cooperate with the blocks 22 and 24, and may be secured in adjusted position against the blocks by binding screws 33 which extend through elongated slots 34 in the members 30 and 31.

The shuttle-engaging faces of the members 30 and 31 are curved to fit the corresponding end portions of the shuttle S and are preferably faced with strips of leather 36. The stop members 30 and 31 are so adjusted on the serrated blocks 22 and 24 that they will simultaneously engage the upper and lower end surfaces of the shuttle S and that they will stop the shuttle in correct position for ejection from the auxiliary shuttle box.

The preferred position is indicated in Fig. 2, in which it will appear that the shuttle S is so located by the stop members 30 and 32 that the point of the shuttle S does not enter the hole in the picker 15 and consequently does not require to be dragged or forced out of the picker during ejection or upon shifting movement of the shuttle box.

Having thus described my invention and the advantages thereof, I do not wish to be limited to the details herein disclosed, otherwise than as set forth in the claims, but what I claim is:

1. In a shuttle changing loom, an auxiliary shuttle box, means fixed relative to said box in position to engage a shuttle at each side of the shuttle point and to positively limit entering movement of said shuttle into said

box, said shuttle-engaging means and said shuttle box having cooperating serrated surfaces by which longitudinal displacement of the engaging means is prevented.

- 5 2. In a shuttle changing loom, a regular shuttle box, an auxiliary shuttle box vertically aligned with said regular shuttle box and movable vertically into alignment with the active shuttle, means fixed relative to said
- 10 auxiliary box in position to engage an approaching shuttle at each side of the entering shuttle point and to positively limit entering movement of said shuttle into said auxiliary box and to prevent the point of the shuttle
- 15 entering the picker or engaging the picker during relative vertical movement of said shuttle and picker, and means to adjustably position said engaging means and to hold said adjusted engaging means from longitudinal displacement.

In testimony whereof I have hereunto affixed my signature.

RICHARD GREENLEAF TURNER.
